United States Patent

Des. 240,882
Patented Aug. 10, 1976

240,882

COVER FOR A DOMESTIC APPLIANCE

Annette E. Knight, 10238 Burman,
Houston, Tex. 77029

Filed July 25, 1974, Ser. No. 487,205

Term of patent 14 years

Int. Cl. D6—06

U.S. Cl. D6—269

FIG. 1

FIG. 3

FIG. 2

FIG. 1 is a front perspective view of a cover for a domestic appliance showing my new design;

FIG. 2 is a rear perspective view; and

FIG. 3 is a second embodiment of the design of FIG. 1.

I claim:

The new, original and ornamental design for a cover for a domestic appliance, as shown.
